[57] CLAIM

The ornamental design for a canape maker or the like, as shown and described.

DESCRIPTION

FIG. 1 is a perspective view of a canape maker or the like having a circular cross-section with the piston fully inserted showing my design;

FIG. 2 is a similar view with the piston fully retracted;

FIG. 3 is a bottom plan view thereof;

FIG. 4 is a perspective view of an alternate embodiment of a canape maker or the like having a square cross-section with the piston fully inserted showing my design;

FIG. 5 is a similar view with the piston fully retracted;

FIG. 6 is a bottom plan view thereof;

FIG. 7 is a perspective view of an alternate embodiment of a canape maker or the like having a hexagonal cross-section with the piston fully inserted showing my design;

FIG. 8 is a similar view with the piston fully retracted;

FIG. 9 is a bottom plan view thereof;

FIG. 10 is a perspective view of an alternate embodiment or the like having an elliptical cross-section with the piston fully inserted showing my design;

FIG. 11 is a similar view with the piston fully retracted; and

FIG. 12 is a bottom plan view thereof.
